O. R. HUKLE,
CARBURETER.

APPLICATION FILED AUG. 16, 1915. RENEWED SEPT. 26, 1919.

1,340,956.

Patented May 25, 1920.

UNITED STATES PATENT OFFICE

OSCAR R. HUKLE, OF JOLIET, ILLINOIS.

CARBURETER.

1,340,956.

Specification of Letters Patent. Patented May 25, 1920.

Application filed August 16, 1915, Serial No. 15,765. Renewed September 26, 1919. Serial No. 326,563.

To all whom it may concern:

Be it known that I, OSCAR R. HUKLE, a citizen of the United States of America, and a resident of Joliet, county of Will, and 5 State of Illinois, have invented certain new and useful Improvements in Carbureters, of which the following is a specification.

The main objects of this invention are to provide a carbureter having improved 10 means for regulating the admission of fuel to the mixing chamber; to provide improved means for effecting a uniform mixture of the oil and air in the mixing chamber; and to provide an improved arrangement of 15 these means on the carbureter casing.

An illustrative embodiment of this invention is shown in the accompanying drawing, in which:

Figure 1 is a sectional elevation of the 20 improved carbureter.

Fig. 2 is a plan of the valve mechanism which controls the air inlets and also operates to facilitate mixing the air and oil.

Fig. 3 is a side elevation of the same.

25 In the construction shown in the drawings, the carbureter comprises a cylindrical casing 1 having a transverse partition 2 subdividing it into an air chamber 3 and a mixing chamber 4. A fuel supply passage 5 extends in from the side of the casing and communicates with an axially disposed oil inlet 6, controlled by needle valves 7 and 8. A plurality of apertures 9 are formed in the partition 2 concentrically of the oil inlet 6 30 and constitute the inlets for admitting air to the mixing chamber. A fuel or gas outlet 10 at the upper end of the casing provides for supplying fuel to the engine.

The needle valve 8 is in the form of a rod 40 and carries a member 11 in the form of a hood rigidly secured thereto so as to move in unison therewith. The member 11 has a comparatively snug fit within the mixing chamber 4 and is arranged to serve as a valve for controlling the admission of air 45 from the air chamber 3 through apertures 9 into the space within the hood. The member subdivides the mixing chamber 4 between the inlets 5 and 9 and the outlet 10 50 into two compartments. Apertures 12 are formed in the member 11 through which the air and oil pass from the compartment below the member to the compartment above. Vanes 13 are arranged on the exterior of 55 the member 11 adjacent to the apertures 12 and are so shaped that the streams of air

drawn through the apertures 12 strike the vanes and cause the member to revolve, thereby facilitating the uniform mixing of air and oil.

The valves 8 and 11 are gravity-actuated and the upper part 14 of the stem 8 is slidably mounted in the cover 15 of the casing 1 so as to guide the valves in their vertical movements.

A block or cam member 16, carried on rods 17 and 18, is slidably mounted on the cover 15 between lugs 19 and 20. A cam surface 21 is formed on the under side of the member 16 and arranged to coact with the tapered end 22 of the stem 14 for limiting the upward movement of the valves 8 and 11. A spring 23 normally urges the cam member 16 into a retracted position and a centrifugal governor 24 shifts the cam 75 member 16 against the action of the spring 23.

The specific form of governor shown herein comprises a wheel or pulley 25 journaled on a shaft 26 secured to the lug 19 and provides a bearing for the rod 17. Bell crank 80 levers 27 are pivoted on the wheel 25 and weighted at one end by balls 28, and connected at their other ends to a cap 29. The cap 29 embraces the end of the rod 17 which is shifted inwardly through the action of 85 the balls 28 being urged outwardly during the rotation of the wheel 25. The wheel 25 is provided with a groove 30 so that it may be connected by means of a belt to the engine.

The spring 23 embraces the rod 18 and is interposed between the cam member 16 and the end of a bolt 31 threaded into the lug 20. The bolt 31 is provided with a head 32 by means of which it is turned for the purpose of adjusting the tension of the spring 23.

The needle valve 7, is mounted in the usual manner in the bottom of the casing 1, and is provided with an arm 33, which is adapted to coact with a dial (not shown) 100 formed around the lower edge 34 of the casing 1 for indicating the flow of oil which is permitted by the valve 7.

The operation of the device shown is as follows:

The suction of the engine causes fuel to be drawn from the mixing chamber 4, which tends to create a vacuum therein. This causes the valves 8 and 11 to elevate so as to admit oil and air within the hood 11 110 through the oil inlet 6 and the apertures 9 respectively. The oil and air then pass

through the apertures 12 into the mixing chamber 4 and in so doing strike the vanes 13 and cause the hood or valve 11 to rotate, thereby stirring up the gases and facilitating uniform mixing thereof.

As the wheel 25 revolves, through its connection with the engine, the balls 28 are urged outwardly causing the levers 27 to act on the cap 29 and, through the rod 17, urge the cam member 16 against the spring 23. As soon as the engine exceeds a certain predetermined speed, the action of the balls 28 is increased so as to cause the cam member 16 to be shifted to bring a lower portion of the cam member 21 over the rod 14. This diminishes the elevation allowed the valves 8 and 11, and decreases the quantity of oil and air admitted into the mixing chamber 4, and accordingly decreases the strength of the mixture admitted to the engine, thereby retarding its action.

As soon as the speed of the engine decreases to normal, the spring 23 overcomes the action of the balls 28 and shifts the cam member 16 into position to permit a greater elevation of the valves 8 and 11.

Although but one specific embodiment of this invention has been herein shown and described, it will be understood that numerous details of the construction shown may be altered or omitted without departing from the spirit of this invention as defined by the following claims.

I claim:

1. A carbureter, comprising a casing provided with a mixing chamber and having an oil inlet and a plurality of air inlets concentrically arranged with respect thereto, a gravity actuated valve member subdividing said chamber into two compartments and arranged to open and close said

air inlets so as to control the admission of air from one to the other of said compartments, and a needle valve carried by said member and arranged to control the admission of oil through said oil inlet, said member having a plurality of apertures providing communication between said compartments. 45

2. A carbureter, comprising a casing provided with a mixing chamber and having an oil inlet and a plurality of air inlets concentrically arranged with respect thereto, a revoluble valve member subdividing said chamber into two compartments and 50 arranged to open and close said air inlets so as to control the admission of air to said mixing chamber, a valve carried by said member and arranged to control the admission of oil through said oil inlets, 55 said member having a plurality of apertures providing communication between said compartments, and vanes arranged on said member adjacent to said apertures, whereby the air and oil passing therethrough 60 will cause said member to revolve.

3. A carbureter, comprising a casing provided with a mixing chamber and having an oil inlet and an air inlet, a bell-shaped reciprocating valve member having apertures therethrough and dividing said chamber into two compartments and controlling the air inlet, a valve controlling the oil inlet and operable in connection with the operation of said member, said member and 70 valve being arranged to admit air and oil into the mixing chamber on the concave side of said member. 75

Signed at Chicago this 13th day of August, 1915.

OSCAR R. HUKLE.
